UNITED STATES PATENT OFFICE.

JOHN A. COTHRAN, OF ST. LOUIS, MISSOURI.

BRICK-MACHINE.

SPECIFICATION forming part of Letters Patent No. 763,264, dated June 21, 1904.

Application filed July 10, 1903. Serial No. 164,967. (No model.)

To all whom it may concern:

Be it known that I, JOHN A. COTHRAN, a citizen of the United States, residing in the city of St. Louis, in the State of Missouri, have 5 invented certain new and useful Improvements in Brick-Machines, of which the following is a full, clear, and exact description, reference being had to the accompanying drawings, forming part of this specification.

10 My invention relates to improvements in brick-machines, having as its object to provide means through which the tension-bars of the machine are shifted vertically on the completion of the stroke of the upper ram to effect movement of the lower ram without the use of additional actuating medium for such lower ram.

15 My invention consists in features of novelty hereinafter fully described, and pointed out in 20 the claims.

25 Figure I is a side view of a brick-machine embodying my improvement. Fig. II is a vertical section taken on line II II, Fig. I, with parts appearing in elevation. Fig. III is a vertical section taken on line III III, Fig. II, with parts appearing in elevation. Fig. IV is a horizontal section taken on line IV IV, Fig. III. Fig. V is a perspective view of one of the upper - ram - limiting wedge-blocks. Fig. VI is a horizontal section taken 30 on line VI VI, Fig. III.

35 Fig. 1 designates a drive - wheel that may be driven by power suitably applied thereto and which carries a cam 2 (shown in dotted lines, Fig. I) and a cam 3.

40 Fig. 4 is a lever pivotally mounted at 5 in the frame of the machine and bearing at its rear end a roller 6, that operates in the cam 2 of the drive-wheel 1. Pivoted to the lever 4 at 45 7 is a pitman 8, that leads to the connecting-pivot 9 of an upper toggle-link 10 and a lower toggle-link 11. The upper toggle-link 10 is provided with a head 12, bearing trunnions 13, and the lower toggle-link 11 is pivoted to an upper ram 14, that carries plungers 15.

16 is the mold-box, situated beneath the upper ram 14 to receive its plungers 15.

17 designates the lower ram, which carries plungers 18 to operate in the mold-box 16 on 50 moving upwardly thereto. This lower ram

is carried by a shaft 19, that receives the pivotal connection of the forward end of a lever 20, that is pivotally mounted at 21, and the rear arm of which receives the engagement, of the cam 3 to rock said lever and elevate 55 the lower ram in the discharge of the bricks from the mold-box 16. The parts thus far described are old, and no invention *per se* is herein claimed for them.

22 designates the upright side frames of the machine, which are provided with vertical slots 23, into which the ends of the upper ram 14 project and operate therein, the ends of the ram being grooved to form tongues 24, that project through the slots 23, as seen in Figs. 60 II and VI. The upper ends of the side frames 22 contain slots 25, in which the trunnions 13 of the upper-toggle-link head 12 fit and rest, as seen in Figs. I and II. At the lower ends 65 of the side frames are vertical slots 26, in which the lower-ram-carrying shaft 19 operates.

27 designates tension-bars fitted in vertical grooves 28 in the side frames 22 for vertical movement therein. These tension-bars extend loosely through the tongued ends of the upper ram 14, and their upper ends are journaled to the upper-toggle-link-head trunnions 13, as seen in Figs. II and IV. At the lower 70 ends of the tension-bars 27 are vertical slots 29, through which the lower ram, carrying shaft 19, passes, as seen in Figs. II and III.

30 designates lift - fingers carried by the lower ram 17 and extending through the slots 29 in the tension-bars 27. 80

31 designates wedge-blocks mounted upon the side frames 22 and extending through the slots 23 therein at the bottoms of said slots, so as to occupy a position in the path of downward travel of the ends of the upper ram 14 90 to thereby serve as stops to limit the downward movement of said ram. As hereinbefore mentioned, the ends of the upper ram project into the slots 23 in the side frames, and they are therefore in the same vertical 95 plane as the wedge-blocks. Each of these wedge-blocks is connected to the side frames 22 by adjustment-screws 32, (see Figs. I and II,) through the medium of which the wedge-blocks may be adjusted inwardly or outwardly 100

to regulate the degree of downward travel of the upper ram as it approaches the mold-box 16.

33 designates cams carried by the upper-
5 toggle-link head 12 at the forward side there-
of, and 34 designates brackets projecting from the inside faces of the side frames 22 in the path
of movement of said cams 33 when the toggle-
link head 12 is rocked in the actuation of the
10 machine. Surmounting the brackets 34 are
removable wedge-shaped wear-blocks 35, that
receive the direct bearing of the cams 33.

In the practical operation of my machine
when the drive-wheel 1 is rotated the pitman
15 8, connected to the lever 4, is reciprocated
rearwardly through the action of said lever
due to its engagement with the cam 2 of said
drive-wheel and the toggle-links 10 and 11
are drawn rearwardly by said pitman, which,
20 being connected to their uniting-pivot 9, tends
to carry said toggle-links into alinement with
each other. On the movement of said toggle-
links the upper ram 14 is forced downwardly
toward the mold-box 16 and its plungers 15
25 enter into said box. The movements of the
parts up to this point are similar to those in
brick-machines heretofore made. In my con-
struction when the upper ram 14 reaches the
wedge-blocks 31 its downward movement
30 ceases, owing to its engagement with the
wedge-blocks before the toggle-links 10 and
11 have completed their movement. As a
consequence of the stoppage of travel of the
upper ram the toggle-link 10 is forced up-
35 wardly, its trunnions 13 riding in such di-
rection in the slots 25 contained by the side
frames 22. In the upward travel of said trun-
nions the tension-bars 27 are moved in verti-
cal lines by reason of their being hung on
40 the trunnions 13. As the tension-bars ascend
their lower ends within the slots 29 are brought
into engagement with the lift-fingers 30, pro-
jecting from the lower ram 17, to cause verti-
cal movement of said ram and carry the plun-
45 gers 18 into the mold-box in opposition to the
plungers 15 of the upper ram 14. It will
therefore be seen that the toggle-links 10 and
11 serve to actuate both of the plunger-car-
rying rams 14 and 17, the former directly and
50 the latter through the medium of the tension-
bars, without the use of any additional agent
to effect their movement in the brick-pressing
operations.

The cams 33, carried by the upper-toggle-
55 link head 12, are designed for service in effect-
ing movement of both of the rams 14 and 17
in unison just after the brick-pressing oper-
ations have been carried out. The object in
so moving the rams is to obviate the occur-
50 rence of lines of disintegration in the bricks,
which are frequently found therein. Just be-
fore the trunnions 13 have reached the limit
of their upward movement in the slots 25 the
cams 33 strike the wear-plates 35 on the brack-
65 ets 34, and as the upper-toggle-link head con-

tinues to rotate the toggle-link 10 is lifted,
owing to the fulcrumage of said cams on said
wear-plates, to thereby occasion lifting action
of the toggle-links 10 and 11, upper ram 14,
and the tension-bars 27 and lower ram 17. 70
By this upward movement of the parts the
rams are moved in unison with each other,
while the bricks are held between their plun-
gers, with the consequent result that in the
75 shifting of the bricks in plastic form in the
mold-box they are rendered of a more com-
pact mass to solidify them and avoid the pres-
ence of lines of disintegration in the finished
bricks.

I claim as my invention— 80

1. In a brick-machine, the combination of a
frame, a mold-box, a pair of rams for move-
ment to said mold-box, means for operating
one of said rams, means for stopping the move-
ment of said last-named ram previous to the 85
completion of the pressing action, and ten-
sion-bars having connection with said ram-
operating means and arranged to engage the
second ram to move it toward the mold-box
after the movement of the first ram is stopped, 90
substantially as set forth.

2. In a brick-machine, the combination of a
frame, a mold-box mounted in said frame,
upper and lower rams for movement to said
mold-box, means for operating said upper 95
ram, tension-bars having connection with
said upper-ram-operating means, means
whereby the movement of said upper ram is
stopped in its downward travel previous to the
completion of the pressing action, and means 100
whereby said tension-bars are caused to en-
gage and lift said lower ram after the down-
ward movement of the upper ram is stopped,
substantially as set forth.

3. In a brick-machine, the combination of a 105
frame, a mold-box, upper and lower rams for
movement to said mold-box, toggle-links con-
nected to said upper ram and having loose
engagement with said frame, means for mov-
ing said toggle-links to depress said upper 110
ram, tension-bars suspended from said links,
means for limiting the downward movement
of said upper ram previous to the completion
of the pressing action, and means whereby
said lower ram is engaged by said tension- 115
bars to lift the lower ram after the downward
travel of the upper ram has ceased, substan-
tially as set forth.

4. In a brick-machine, the combination of a 120
frame, a mold-box, upper and lower rams for
movement to said mold-box, a toggle-link con-
nected to said upper ram, a toggle-link con-
nected to said first-named link and having
trunnions reciprocally positioned in said 125
frame, wedge-blocks mounted on said frame
beneath the upper ram to limit its downward
travel previous to the completion of the press-
ing action, tension-bars suspended from said
toggle-link trunnions, and means whereby
said tension-bars engage said lower ram to 130

lift it after the movement of the upper ram has been stopped by said wedge-blocks, substantially as set forth.

5. In a brick-machine, the combination of a frame, a mold-box, upper and lower rams for movement to said mold-box, a toggle-link connected to said upper ram, a toggle-link connected to said first-named link and having trunnions reciprocally positioned in said 10 frame, wedge-blocks mounted on said frame beneath the upper ram to limit its downward travel previous to the completion of the press-

ing action, means for adjusting said wedge-blocks, tension-bars suspended from said toggle-link trunnions, and means whereby said tension-bars engage said lower ram to lift it after the movement of the upper ram has been stopped by said wedge-blocks, substantially 15 as set forth.

JOHN A. COTHRAN.

In presence of—

NELLIE V. ALEXANDER,
BLANCHE HOGAN.
